UNITED STATES PATENT OFFICE.

ADOLPH CLEMETSON AND HARRY G. HOLLOWAY, OF HOWARD, SOUTH DAKOTA.

STOCK-RELEASING DEVICE.

1,212,017.

Specification of Letters Patent. Patented Jan. 9, 1917.

Application filed May 9, 1916. Serial No. 96,459.

To all whom it may concern:

Be it known that we, ADOLPH CLEMETSON and HARRY G. HOLLOWAY, citizens of the United States, residing at Howard, in the county of Miner and State of South Dakota, have invented new and useful Improvements in Stock-Releasing Devices, of which the following is a specification.

The present invention relates to improvements in an apparatus for releasing stock from a stable in the event of a fire in the stable or barn, and it is the aim of the invention to provide novel and improved means for simultaneously releasing the stock and forcing the latter to be driven out of the stable.

With the above and other objects in view, the invention consists in the novel features, details of construction and combination of parts which will hereinafter be more fully set forth, illustrated in the accompanying drawings and pointed out in the appended claims.

Figure 1 is a perspective view of a stable equipped with the appliance embodying the invention; Fig. 2 is a longitudinal section taken through the manger rail, illustrating the release bar in locked position; Fig. 3 is a transverse section taken through Fig. 1 of the drawing; Fig. 4 is a detail perspective view of the releasing bar; and Fig. 5 is a perspective view of the clip.

Referring more particularly to the accompanying drawings, in which like characters of reference refer to corresponding parts in the several views, 5 denotes a stable including side walls 6 and an end wall 7, and having the usual stalls 8 located thereon.

The character 9 designates the manger rail traversing the forward end of the stalls and provided with a plurality of spaced alining U-shaped sockets 10 formed in the upper longitudinal edge thereof. A plurality of clips 11 are provided and adapted to straddle the upper edge of the manger rail and overlie the sockets thereof. Each of said clips is constructed from a single blank of metal bent in substantially U-form providing a pair of spaced parallel limbs 12 connected to one another through the medium of a connecting portion 13. These clips are permanently secured to the manger rail by fasteners 14. The material forming the connecting portion 13 is stamped upwardly to provide the same with a rib 15 which extends through the longitudinal center of the

clip and presents a groove 16, the purpose of which will be hereinafter more fully set forth as the description of the invention is proceeded with. The connecting portion 13 is further provided through its transverse center with a slot 17 terminating in the upper edges of the limbs 12 of the clip and adapted to receive therein the halter rings 18 when the stock is hitched to the manger rail, as will be apparent from the drawing. The point of connection of the limbs with the connecting portion is convexed or curved as at 19, providing the clip with spaced parallel guide grooves 20, and when the clips are in applied position will dispose the guide grooves slightly above the plane of the top edge of the manger rail to permit of the grooves slidably receiving therein the release bar 21. This release bar is preferably constructed from sheet metal and of flat rectangular form bent at spaced intervals throughout the length thereof to provide the same with a plurality of transverse depending U-shaped tongues 22 having a groove 23. Upon the active position of the releasing bar, the tongues 22 thereof are reposed within the sockets 10 for opposite longitudinal sliding movements, and the outer end of the said bar protrudes through the slot 24 formed in one of the side walls 6 of the stable, and extends therebeyond designated by the numeral 25. Pivotedly connected to the extending extremity 25 of the bar is an operating lever 26 for imparting movement thereto. Riveted or otherwise suitably secured to the upper surface of the release bar are hitching pins 27, and said pins are disposed longitudinally of the said bar and in alinement one to the other, defining the offset locking ends 28 thereof in partial obstructing relation over the grooves 23 of the tongues. The said pins have slideable engagement with the groove 16 of the ribs of the clips, and when assuming a locked position, close the slots 17 of the clips and retain the halter ring 18 within the groove 23 of the tongues. Upon operating the lever 26 to release the stock from the manger rail, a pull is exerted on the lever 26, retracting the pins to non-obstructing relation with respect to the slot 17, and allowing the animals or stock to be simultaneously and automatically released without necessitating the party releasing the stock being compelled to enter the stable.

In order to assure the stock leaving the

stable in case of fire, upon the release of the same from the manger rail, we provide a whipping device 29, which is illustrated as comprising a rod 30 extending in parallelism with the manger rail 9, and forwardly thereof. The said rod is mounted on the end wall 7 of the stable for reverse movements by means of supporting clips 31, and movement is imparted to the rod through 10 the medium of the crank 32, which also passes through one of the side walls of the stable in order that this whipping device may be operated from without the stable. Permanently connected with the rod 30 at 15 intervals throughout the length thereof is a series of members 33, having permanently connected therewith lashing members 34.

From the foregoing description, taken in connection with the accompanying drawing, 20 the advantages of construction and of the method of operation will be readily apparent to those skilled in the art to which the invention relates, and while we have described the principles of operation of the invention, together with the device which we now consider to be the best embodiment thereof, we desire to have it understood that the device shown is merely illustrative, and that such changes may be made when desired as are within the scope of the claims appended thereto.

We claim:

1. In combination with a stable having a manger rail therein formed with a series of 35 sockets, a releasing bar formed with spaced grooved tongues, the tongues of the releasing bar being slidably mounted within the sockets of the manger rail, clips straddling the releasing bar and secured to the manger 40 rail, each clip having a slot, a series of hitching members secured to the releasing bar, and means connected with the releasing bar for moving the hitching members into and out of registration with the slots of the clips 45 substantially as and for the purpose specified.

2. A device of the class described embodying a manger rail formed with a series of

sockets, a releasing bar having grooved tongues adapted to extend within the sockets of the manger rail for opposite sliding movements, a clip having a slot disposed over the sockets formed in the manger rail and provided with spaced guide grooves, a series of hitching members secured to the releasing bar and disposed over the grooved tongues, means connected with the releasing bar for moving the hitching members in obstructing and non-obstructing relation with respect to the slots of the clips. 50

3. A device of the class described embodying a manger rail formed with a series of 55 sockets, a releasing bar having grooved tongues adapted to extend within the sockets of the manger rail for opposite sliding movements, a clip having a slot disposed over the sockets formed in the manger rail and provided with spaced guide grooves, a series of hitching members secured to the releasing bar and disposed over the grooved 60 tongues, means connected with the releasing bar for moving the hitching members in obstructing and non-obstructing relation with respect to the slots of the clips, and manually operable means disposed in advance of the 65 manger rail for driving the stock from the 70 stable. 75

4. In a device of the class described, a stationary member formed with a series of 80 sockets, a bar having grooved tongues reposed upon the fixed member with the tongues thereof disposed within the sockets of said member, a series of pins connected with the bar and arranged in longitudinal alinement one to the other, and a slotted clip 85 having a groove for slidably receiving the pin, means for imparting movement to said bar in opposite directions, said pins upon the movement of the bar in one direction adapted to close the slot of the clip substantially 90 as and for the purpose specified.

In testimony whereof we affix our signatures.

ADOLPH CLEMETSON.
HARRY G. HOLLOWAY.
